ESCAPEMENT ADJUSTING DEVICE

Ernest Alphonse Derungs and Oscar Chatelain,
Le Locle, SwitzerlandApplication October 27, 1943, Serial No. 507,854
In Switzerland October 21, 1942

3 Claims. (Cl. 185—46)

1

Object of the invention is an adjusting device which possesses an escapement whose movements are adjusted by a vibrator lever fixed to the axle of a balance whose oscillations can be influenced with regard to their period during the running of the device.

Such a device is quite independent of variations in temperature and effects of adhesion between surfaces subjected to relative displacements, as is the case in analogous mechanisms used up to date.

By preference, a simple and robust vibrator lever is used e. g. one of the well-known type with equidistant pallets. The properties of these escapements need not be described in detail. However, one is not restricted to the use of this kind of escapements.

The period of oscillation is varied by modifying the amount of inertia of the balance fixed to the axle of the vibrator lever by displacing masses.

The accompanying drawing illustrates, by way of examples, one embodiment of the adjusting device according to the invention.

Figs. 1 and 2 show only those parts of the apparatus which are necessary for understanding the invention.

Referring now to Figs. 1 and 2, the reference characters 10 and 11 designate the upper and lower plate of the part of the apparatus on which the adjusting device is mounted. On these plates 10 and 11 an escape wheel 12 is journaled, cooperating with a vibrator lever 13 of the well-known type with equidistant pallets. The operation of this escapement, that is, the cooperation of this escape wheel with this lever is well-known to those skilled in the art and need not be described in detail.

The escape wheel receives its movement from a pinion 14 cooperating with a non-illustrated gearing. The axle of the vibrator lever 13 is a tube 15 which is supported on the plate 11 by a shoulder and ends at the top in a point 16 journaled on a ball bearing 17.

In the interior of the tube 15 a rod 18 is slidably placed, carrying a pin 19 which traverses cut-outs 20 in the wall of the tube 15. Besides this, pin 19 goes through a collar 21 connected by means of rods 22 with the shorter arm of bent levers 23 whose longer arms carry weights 24. These bent levers 23 are pivoted on a ring 25 fixed to the tube 15.

A spring 26 is inserted between the ring 25 and the collar 21.

The lower end of the rod 18 rests on a bent lever 27 whose shorter arm is attached to the wire 28 of a Bowden cable 29.

It will be easily understood that, by pressing upon the button 30, lever 27 is rotated and lifts the rod 18 and, with it, the collar 21 and the

2

rods 22, whereby the levers 23 are tilted and the weights 24 approached to the axis of oscillation of the vibrator lever 13. By doing this, the moment of inertia of the balance fixed to the lever 13 and formed by the weights 24 and their accessories is diminished. During the above operation the axial pressure exerted upon the rod 18 and tube 15 is received by the ball bearing 17. On letting the button 30 go the spring 26 moves the weights 24 away from the axis of oscillation of the vibrator lever 13.

It may thus be seen that during operation of the apparatus it is possible to modify the period of oscillation and, in consequence, the movements of the gearings connected with the escape wheel 12 by means of the pinion 14. In this way and if it is a question of a motor with variable power, a suitable braking could be obtained at the start of the motor and a less efficacious braking when the motor is no longer able to give its maximum power. In such a case the button 30 or an equivalent mechanical means is brought into connection with an apparatus indicating, for instance, the tension of a spring motor.

What we claim is:

1. In an adjusting device, an escapement, an axle, a vibrator lever fixed to said axle for controlling the movements of said escapement, a balance mounted on said axle, including masses displaceable in order to modify the moment of inertia of said balance means tending to displace said masses in one direction, and means passing axially through said axle for displacing the masses in the opposite direction.

2. In an adjusting device, an escapement, an axle, a vibrator lever fixed to said axle for controlling the movements of said escapement, a balance mounted on said axle, including rocking levers, and masses fixed to said rocking levers, said rocking levers with said masses being able to move away from and to approach to the oscillation axis of said vibrator lever in order to modify the moment of inertia of said balance and means passing through said axle for radially adjusting said levers.

3. In an adjusting device, an escapement, a tube, a vibrator lever fixed to said tube for controlling the movements of said escapement, a balance mounted on said tube, including rocking levers, and masses fixed to said rocking levers, a slidable rod in the interior of said tube destined to rotate said rocking levers in order to move the masses away from and to approach them to the oscillation axis of said vibrator lever.

ERNEST ALPHONSE DERUNGS.
OSCAR CHATELAIN.
